UNITED STATES PATENT OFFICE.

LOUIS E. BROWN, OF BOSTON, MASSACHUSETTS, ASSIGNOR TO FARRINGTON MANUFACTURING COMPANY, OF BOSTON, MASSACHUSETTS, A CORPORATION OF MAINE.

BOX OR CASE.

1,119,804.

Specification of Letters Patent.

Patented Dec. 8, 1914.

Application filed January 20, 1914. Serial No. 813,313

To all whom it may concern:

Be it known that I, LOUIS E. BROWN, a citizen of the United States, residing at Boston, county of Suffolk, State of Massachusetts, have invented a certain new and useful Improvement, in Boxes or Cases, of which the following is a specification, reference being had therein to the accompanying drawings.

10 My invention relates to boxes or cases covered with plush, leather or a similar material which are designed for holding articles such for instance as watches, or jewelry.

As is well known, cases for watches or of 15 a similar nature, commonly consist of a top and bottom secured together by means of a hinge. It is important that cases of this type should present a finished appearance which is entirely in keeping with their con-

20 tents. Cases of this kind are commonly hinged on the inside and there is a slight relative movement between the outside edges of the top and bottom at the hinged end when the cover is moved on the hinge.

25 Therefore, in order that the parts will not bind when opened the edges are usually spaced apart slightly so that the hinge is then visible. The top and bottom of the box have commonly been covered separately

30 and the covered parts then hinged together, in which case the hinge is visible between the edges of the box and its cover when the box is closed. When it is desired to cover the hinge, a piece of the covering material

35 has been secured to the outer surface of the box and its cover, said piece of covering material extending across the hinge and concealing it. A case covered in this way pre-

40 sent a fairly finished appearance when the case is closed, but when open the covering bags out at the hinge and presents an un-

45 finished appearance. This method of concealing the hinge is inapplicable to plush covered boxes on account of the nature of the material. When plush has been em-
ployed the hinge has either been left ex-
posed, or the covering material for both top
and bottom have been made in a single piece
and applied to the box by hand after the
50 box has been assembled. This is expensive
and the covering bags at the hinge when the
box is open.

55 Applicant's object is to produce a hinged case provided with a covering of any well known finishing material as plush, silk or

leather which completely conceals the hinge heretofore commonly seen when the case is closed and which also does not present a baggy or unfinished appearance when it is open.

60 My invention will be fully understood from the following description taken in connection with the accompanying drawings and the novel features are pointed out and clearly defined in the claims at the close of 65 the specification.

In the drawings Figure 1 is a view in perspective of a case embodying my invention, the case being closed. Fig. 2 is a vertical section on line 2—2 of Fig. 1. Fig. 3 is a 70 section of a portion of the hinged end of the case showing the top open. Fig. 4 is a transverse section taken on line 4—4 of Fig. 2.

Having reference to the drawings there 75 is shown a case of the type commonly employed for holding watches or jewelry. It comprises an upper part or cover A and a lower part or bottom B which are preferably constructed of light metal a, but may 80 equally well be made from other suitable material. The parts referred to are secured together in any well known manner as by a hinge b and a spring catch c both being secured to the inside surface of the bottom 85 and top all as clearly shown in Fig. 2. In order that the parts A and B may be swung on the hinge, the edges f and g at the hinge end of the top and bottom respectively are secured slightly apart as shown in Fig. 2. 90 This prevents undue binding when the cover is opened. Before the parts A and B have been secured together as stated above, the outer surface of each part is covered with a finishing or covering material l such as 95 plush or leather. This may readily be done by placing the covering over the outer surface of the metal of which the part is constructed and lapping it around the edges onto the inside as is clearly shown in the 100 drawings. The covering may then be held in position in any suitable manner as by adhesive. The covered parts are placed together in the position shown in Fig. 2 and a strip of covering material o, the same as 105 that with which the parts are covered, is secured between the outside surface of the hinge and the inner surfaces of the adjacent portions of the top and bottom respectively. As shown in the drawings, the hinge b and 110

strip of material *o* are secured in place by bent lugs 20 forming part of the top and bottom members. The said lugs pass through the hinge covering strip and 5 through suitable slots in the hinge members and are clenched on the inside of the hinge members.

The construction will perhaps be most readily understood by observing that in 10 Figs. 2 and 3 the outer layer is shown at *l*. This is the covering material. The next layer *m* is the metal of which the box member is composed. The next layer *n* is the upturned inner edge of the outer covering 15 material. Interposed between the hinge member *p* and the layer *n* is the hinge covering strip *o* which is of the same material as that of which the covering is made. The last or innermost layer is a hinge spring *q*. 20 It will be seen that the hinge covering strip extends the full width of the hinge and covers that portion of the hinge which would ordinarily be exposed to sight when the box is closed. When the box is opened 25 the very slight fullness of the hinge covering strip extends around the hinge member into the space between the proximate edges of the two box members and conceals the hinge so that the box presents a perfect 30 appearance to the eye both when opened and when closed.

What I claim is:

1. The improved jewelry case comprising a bottom and a top covered with finishing

material, a hinge by which said top and 35 bottom are secured together, and a strip of finishing material interposed between the said hinge and the top and bottom, the said hinge being concealed thereby.

2. The improved jewelry case comprising 40 a top having depending sides, a bottom having upwardly extending sides, an outer covering of finishing material secured to each of said parts and lapped over the edges of 45 said sides, a hinge by which said parts are secured together, said hinge being secured to the inner surface of two corresponding sides, and a strip of finishing material interposed between said hinge and said inner surfaces whereby said hinge is concealed. 50

3. The improved jewelry case comprising a bottom and a top covered with finishing material, a hinge by which said top and bottom are secured together provided with 55 hinge members having slots therein, a strip of finishing material interposed between the said hinge and the top and bottom, and lugs secured to said top and bottom and passing through said strip and said slots whereby said strip is secured in position.

In testimony whereof I affix my signature, in presence of two witnesses this 17th day of January 1914.

LOUIS E. BROWN.
